CLAIM

The ornamental design for a combination jacket and backpack, as shown and described.

DESCRIPTION

FIG. 1 is a front elevational view of a combination jacket and backpack showing my new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof;

FIG. 7 is a front view of the backpack assembled on an enlarged scale thereof;

FIG. 8 is a left side view, the right side being a mirror image thereof; and,

FIG. 9 is a rear view thereof.
